UNITED STATES PATENT OFFICE.

FRITZ H. GIESECKE, OF BRENHAM, TEXAS.

WASHBOARD.

Application filed November 5, 1920, Serial No. 421,833. Renewed February 23, 1924.

To all whom it may concern:

Be it known that I, FRITZ H. GIESECKE, a citizen of the United States, residing at Brenham, in the county of Washington and ⁵ State of Texas, have invented certain new and useful Improvements in a Washboard, of which the following is a specification.

This invention relates to new and useful improvements in a washboard.

¹⁰ One object of the invention is to provide a washboard constructed, in the main, of sheet metal, and which will be very durable.

Another object of the invention is to produce a washboard which is of simple construction and which may be cheaply and easily manufactured.

With the above and other objects in view the invention has particular relation to certain novel features of construction and use, ²⁰ an example of which is given in this specification and illustrated in the accompanying drawings, wherein:—

Figure 1 shows a side view of the device.

Figure 2 shows a vertical sectional view, ²⁵ and

Figure 3 shows a horizontal sectional view.

Referring now more particularly to the drawings, the numerals 1, 1 refer to the side members of the frame and the numeral 2 designates the top thereof, these parts being ³⁰ sheet metal and tubular in form. Around the inner sides of the frame members 1, 1 and 2 the material thereof is thrown out forming parallel ribs 3, 3 and 4, 4.

A single sheet of metal 5 has its upper end fitted between the ribs 4, 4 and its edges fitted between the corresponding ribs 3, 3, ⁴⁰ said sheet being clamped between said ribs and by them held in place. Near its upper end this sheet has a double fold, the folds of metal being brought closely together, thus forming the ledges 6, 6 projecting out in opposite directions and forming soap shelves

or retainers. Beneath these ledges the sheet ⁴⁵ 5 is transversely corrugated and its lower end is bent into tubular form around the transverse anchor rod 7, whose ends are anchored to the side members of the frame. This tubular part of said sheet has drain ⁵⁰ ports 8 to drain the water therefrom and prevent rusting when the board is not in use.

Wooden legs 9, 9 are inserted into the lower ends of the tubular side members. ⁵⁵ These will not scar or injure the bottom of the tub in which the board is used and will prevent the slipping of said board. They can easily be removed when worn out and new ones substituted therefor.

What I claim is:

A washboard, including a frame having a top and side members formed of sheet metal, tubular in form, parallel ribs spaced apart extending entirely around the inner sides of the frame and thrown out from ⁶⁰ the material thereof, a transverse anchor rod secured at its ends to said side members, a single sheet of metal whose corresponding edges are fitted between said ribs and are clamped by them to secure said ⁶⁵ sheet in place, said sheet being formed near its upper edge with a double fold forming ledges which project out in opposite directions and the lower edge of said sheet being bent around said anchor rod and provided with drain ports, the portion of the sheet between said anchor rod and said ledges being transversely corrugated, and removable wooden legs inserted into the lower ⁷⁰ ends of said tubular side members. ⁷⁵

In testimony whereof I have signed my name to this specification in the presence of two subscribing witnesses.

FRITZ H. GIESECKE.
